UNITED STATES PATENT OFFICE.

AUGUST F. SCHICK, OF PORTLAND, OREGON, ASSIGNOR TO GEORGE LAWRENCE COMPANY, OF PORTLAND, OREGON.

SADDLE.

1,159,715.

Specification of Letters Patent.

Patented Nov. 9, 1915.

Application filed October 3, 1914. Serial No. 864,767.

To all whom it may concern:

Be it known that I, AUGUST F. SCHICK, a citizen of the United States, residing at Portland, in the county of Multnomah and 5 State of Oregon, have invented certain new and useful Improvements in Saddles; and I do hereby declare the following to be a full, clear, and exact description of the invention, such as will enable others skilled in 10 the art to which it appertains to make and use the same.

This invention relates to saddles and more particularly to the saddle tree construction which is adapted to any class of saddles, but 15 is more especially designed for saddles such as are used by ranchmen or stockmen upon the plains.

One of the principal objects of this invention resides in the novel construction of the 20 cantle of the saddle tree for preventing the lower vertebrae of the spine of the rider from contacting with the upper central edge of the cantle of the saddle tree, thereby obviating the dangerous results and consequences 25 therefrom and the serious objections to the make of saddles now in use.

Another object of this invention resides in the construction of the pommel arc of the saddle tree wherein their upper outer 30 portions project rearwardly and slightly outwardly to provide enlarged knob members. These knob members being also acutely under-cut to provide broad faced recesses for the reception of the thighs of the 35 rider to thereby greatly assist him in retaining his position upon the back of the animal.

A further object of this invention resides in the construction of a saddle and the saddle tree therefor, which is simple and novel 40 in construction, efficient and durable and which can be manufactured and sold at a nominal cost.

The invention will be more clearly understood by the following specification, the subject matter of the claim, and the views illustrated in the drawings, in which,

Figure 1 is a perspective view of the saddle in its complete form. Fig. 2 is a side 50 elevation of the saddle tree partly broken away and shown in section showing the novel construction of the cantle and pommel. Fig. 3 is a vertical transverse sectional view of the saddle tree showing the novel construction of the cantle thereof.

Referring to the drawings, 1 denotes the spaced side bars of the saddle tree, similar to that of the McClellan type of saddles and 2 the cantle of the saddle tree. This cantle embraces the upper edges of the side bars 1 60 adjacent the rear ends thereof and is of a concavo-convex formation as shown at 3, to provide a more efficient seat. The upper central edge of the cantle 2 is provided with the enlarged and indented or recessed portion 4, the inner edge of the recess 4 being provided with the broad bevel 5. The recess 4 and its bevel 5 are preferably curved downwardly and faced inwardly and efficiently prevent the lower spinous processes 70 of the spine of the rider from contacting with the upper central edge of the cantle 2, thereby eliminating injury to the spine. The recess 4 also serves as a handhold for the rider when mounting the horse. 75

Adjacent the forward ends of the sides 1 and embracing the same is the pommel arc 6 provided with the usual pommel knob 7. The rear outer edges of the upper portions of the pommel arc 6 are provided with the 80 rearwardly and slightly outwardly extending projections or knobs 8, the projections or knobs 8 being provided with the broad faced and acutely under cut members 9. These members 9 act conjunctively with the 85 upper portions 10 of the side bars 1 and provide enlarged recesses for the accommodation or reception of the thighs of the rider for greatly assisting him in retaining his position within the saddle upon the back of 90 a vicious or fractious animal.

The side bars 1, the cantle 2, the pommel arc 6 and the pommel knob 7 are suitably formed to provide an efficient structure. The same are made in several parts and secured together in assembled relation by any suitable means. The entire structure is covered with the usual raw hide covering 11 secured thereon by the usual thong stitching 12, the metallic staples 13 and the customary 100 brass or other metallic headed tacks 14.

It will be seen from the foregoing description of the novel saddle tree that by the provision of the curved recess 4 and the inner beveled edge 5 thereof, it is impossible for 105 the lower portion of the rider's spine to contact with the upper central edge of the cantle of the saddle.

Another important feature of this invention resides in the rearwardly extended por- 110

tion or knobs 8 of the pommel are 6 being provided with the sloping and broad faced under cut portions 9, which in conjunction with the upper portions 10 of the sides 1, 5 provides enlarged recesses or compartments for the thighs of the rider for preventing him from being thrown by vicious animals. Therefore, in this invention a safe, healthy and comfortable saddle and saddle tree are 10 provided which now supplies the long felt want in saddle construction.

While I have here shown the preferred embodiment of my invention, I hereby reserve the right to make such alterations and 15 variations therein from time to time as I may deem expedient and which will neither depart from the spirit of this invention nor conflict with the scope of the claim.

Copies of this patent may be obtained for five cents each, by addressing the "Commissioner of Patents.
Washington, D. C."

What I claim as new and desire to secure by Letters-Patent of the United States, is:— 20

A saddle, comprising a tree consisting of spaced side bars, and a cantle consisting of an integral member embracing and securing together the rear end portions of said side bars, said cantle having its upper central 25 edge formed with an enlarged longitudinally curved recess and beveled to face inwardly to prevent contact of the upper edge of said cantle with the spine of the rider.

In testimony whereof I have signed my 30 name to this specification in the presence of two subscribing witnesses.

AUGUST F. SCHICK.
